UNITED STATES PATENT OFFICE

LEON L. ALLYN, OF KALAMAZOO, MICHIGAN, ASSIGNOR TO MASTER-CRAFT CORPORATION, OF KALAMAZOO, MICHIGAN

TEMPORARY BINDER

Application filed November 11, 1929. Serial No. 406,229.

The main object of this invention is to provide a temporary binder having pivoted binding members and a movable transfer bar which is very convenient to manipulate.

5 A further object is to provide a temporary binder having a pivoted binding bar provided with posts in which the binding bar may swing on its pivots in opening and closing the book but is yieldingly supported with its 10 posts in upright position when the binder is open.

Objects pertaining to details and economies of my invention will definitely appear from the description to follow. The invention is 15 defined in the claims.

A structure embodying the features of my invention is clearly illustrated in the accompanying drawings, in which:

Fig. 1 is a fragmentary inside perspective 20 view of a binder embodying the features of my invention.

Fig. 2 is a fragmentary view in section on line 2—2 of Fig. 1 with the binding or post bar in upright position.

25 Fig. 3 is a fragmentary view corresponding to that of Fig. 2 with the binding bar in another position.

Fig. 4 is a perspective view of the sheet body and transfer bar removed from the 30 covers.

Fig. 5 is a sectional view on line 5—5 of Fig. 4.

Fig. 6 is a fragmentary sectional view on line 6—6 of Fig. 4.

35 In the embodiment illustrated the covers 1 and 2 are adjustably connected by means of the binding strips 3. A suitable adjusting mechanism for the binding strips is illustrated in the patent to Bushong, No. 914,383, dated March 9, 1909. This embodiment has a flexible back 4. The cover 1 carries a binding bar 6 provided with posts 7 while the cover 2 carries a binding bar 21. These binding bars are pivotally mounted on their respective covers, the binding bars being provided with rearwardly projecting pivot ears 22 engaging the pivot pintles 23 which serve to support the binding bars so that they may swing bodily in an arc relative to the covers.

40 The transfer bar 8 is removably associated

with the bar 21, it being provided with lugs 9 detachably engageable with holes 10 in the binding bar 21. The transfer bar 8 is provided with two posts 11 opposite the lugs 9.

The sheet body 12 has holes 13 adapted to receive the posts 7 of the binding bars 6 and holes 14 adapted to receive the posts 11 of the transfer bar 8 so that the sheets may be lifted as a unit from the posts 7 and replaced thereon as a unit.

55 In order to facilitate the manipulation of the binder I provide means for supporting the post bar 6 in upright position. This means in the structure illustrated comprises a blade spring 15 riveted to the inner side 60 of the cover 1 at 16 and having its free end 17 curved outwardly relative to the longitudinal plane of the cover and lying in engagement with the binding bar 6 so that when this binding bar is swung to its erected position, as shown in Fig. 2, it is yieldingly supported by the spring in suitable position to receive the sheet body. This very greatly facilitates the manipulation of the binder, particularly the placing of the sheets therein.

70 I have illustrated my improvements as embodied in binders having flexible binding strips. I have not attempted to illustrate or describe various other adaptations or embodiments of my improvements as it is believed that this disclosure will enable those skilled in the art to embody or adapt the same as may be desired.

75 Having thus described my invention what I claim as new and desire to secure by Letters Patent is:

1. In a temporary binder, the combination of coacting covers, connecting means for the covers, binding bars pivotally mounted on the covers, one of said binding bars being 80 provided with posts, a transfer bar provided with posts removably associated with the other binding bar, and a spring means for yieldingly supporting said post-carrying binder bar in upright position on its cover.

90 2. In a temporary binder, the combination with covers, and connecting means for said covers, of a binding bar pivotally mounted on one of said covers and provided with posts, a transfer bar provided with posts re-

movably associated with said binding bar, and a blade spring having an outwardly curved free end mounted on the cover carrying said binding bar to engage the inner side thereof and acting to yieldingly support the bar with its posts in upright position.

3. In a temporary binder, the combination with covers, and connecting means for said covers, of a binding bar pivotally mounted on one of said covers and provided with posts, a transfer bar provided with posts removably associated with said binding bar, and a spring means for yieldingly supporting said binding bar with its posts in upright position on its cover.

4. In a temporary binder, the combination with covers, and connecting means for said covers, of a binding bar pivotally mounted on one of said covers and provided with posts, a transfer bar provided with posts removably associated with said binding bar and a blade spring having an outwardly curved free end mounted on the cover carrying said binding bar to engage the inner side thereof and acting to yieldingly support the bar with its posts in upright position.

5. In a temporary binder, the combination with covers, and connecting means for said covers, of a binding bar pivotally mounted on one of said covers and provided with posts, a transfer bar provided with posts removably associated with said binding bar and a spring means for yieldingly supporting said binding bar with said posts in upright position on its cover.

In witness whereof I have hereunto set my hand.

LEON L. ALLYN.
